(57) CLAIM

The ornamental design for a stylus, as shown and described.

DESCRIPTION

FIG. 1 is a perspective view of a stylus, showing the new design;

FIG. 2 is a front view of the stylus of FIG. 1;

FIG. 3 is a rear view of the stylus of FIG. 1;

FIG. 4 is a left side view of the stylus of FIG. 1;

FIG. 5 is a right side view of the stylus of FIG. 1;

FIG. 6 is a top plan view of the stylus of FIG. 1; and,

FIG. 7 is a bottom plan view of the stylus of FIG. 1.

The claimed design is directed to the collective appearance of the articles shown.

The broken lines in the drawings are employed for illustrative purposes only and form no part of the claimed design.
